COMBINATION TABLE AND CHAIR

Harry Freedman, New York, N. Y.

Application November 29, 1944, Serial No. 565,621

8 Claims. (Cl. 155—124)

1

This invention relates to a combination table and chair.

An object of this invention is to provide a device of the character described which may be collapsed compactly and which may easily be opened up to provide a table and chair.

Another object of this invention is to provide a device of the character described in which the table may be tilted to any desired angle and which may also be moved in its own plane and fixed in adjusted position.

Another object of this invention is to provide a device of the character described supported like a tripod by two legs at the rear beneath the seat, and on one leg on the front beneath the table top.

Yet a further object of this invention is to provide a neat, compact device of the character described which shall be relatively inexpensive to manufacture, easy to assemble and manipulate, and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a side elevational view of a combination table and chair embodying the invention;

Fig. 2 is a bottom plan view thereof;

Fig. 3 is a rear end view thereof;

Fig. 4 is a side elevational view of the device partially collapsed;

Fig. 5 is a side elevational view of the device fully collapsed;

Fig. 6 is a cross-sectional view taken on line 6—6 of Fig. 1; and

Fig. 7 is a partial view of the front leg and illustrating a modified construction.

Referring now in detail to the drawing, 10 designates a combination table and chair embodying the invention. The same comprises generally a table top 11 and a seat 12. The table top 11 is supported by a front leg 13, and the seat 12 is supported on a rear leg member 14, as will appear hereinafter.

Attached to the underside of seat 12 and adjacent and parallel to the rear edge thereof are a pair of aligned bearings 15. Swiveled or hinged onto the bearings 15 is a rear leg member 14. The

2

same comprises a top horizontal portion 16 and a pair of downwardly extending parallel legs 17. Member 14 may be made of a single piece of round tubular stock. The horizontal portion 16 is journaled in the bearings 15. The legs 17 are interconnected by a horizontal brace 18 disposed above the lower ends of the legs. Pins 16a fixed to portion 16 contact the outer ends of the bearings 15 to prevent side shifting of leg member 14.

Fixed to the underside of seat 12 adjacent the front edge thereof is a sleeve 20 extending longitudinally of the midsection of the seat. At the underside of seat 12 is a tubular rod 21 passing through sleeve 20. One end of said rod is fixed to the middle of horizontal portion 16 of leg member 14. The rod 21 has a T-sleeve 22 at its rear end rotatably receiving said horizontal portion 16. Rod 21 projects forwardly beyond the seat 12 and terminates in a pair of bifurcated apertured ears 24 for the purpose hereinafter appearing.

Attached to the brace 18 at a point somewhat off the middle of said brace is an angular bracket 25 having a forwardly extending apertured finger 26. Hinged to finger 26, as on hinge 27 passing through the aperture in said finger, is one end of a link 27a. Attached to the underside of seat 12 and disposed between sleeve 20 and the forward edge of said seat, is a bracket 29 having a downwardly extending finger 30. Hinged to finger 30 as on pivot 31, is one end of a link 32. Link 32 is pivoted to an intermediate portion of link 27a as at 33. Pivoted to the other end of link 27a, as at 34, is a link 35 disposed below rod 21. The forward end of link 35 and the bifurcated portion 24 of rod 21 are hinged to a pair of brackets 40, 41 fixed to the lower and upper ends, respectively, of a tubular sleeve 42 of square cross section. The front leg 13 is preferably of square tubular construction so that it cannot rotate in sleeve 42.

Fixed to leg 13 is a pin 44 adapted to be received in a notch 45 at the lower end of tube 42 to limit sliding movement of the leg relative to the tube in one direction. Fixed to the leg 13, adjacent the lower end thereof, is a footrest 46 as shown in the drawing.

Attached to the underside of the table top 11 is a longitudinal bracket 50 of angular cross-section. The bracket 50 has a horizontal wall 51 contacting and riveted as at 52, to the underside of table top 11. Extending downwardly from the horizontal portion 51 of bracket 50 is a wall 53 formed with a longitudinal slot 54. At the upper end of the tubular leg 13 is a flat offset wall 55 formed with a through opening. Extending through wall 55 is a bolt 56 which also passes

through said slot 54. Bolt 56 has a head 57 contacting wall 53 of bracket 50. On the bolt is a wing nut 58 for tightening the bolt in any desired adjusted position of the table top. It will now be understood that the table top 11 may be tilted to any desired angle and may also be slidably moved in its own plane and then fixed to adjusted position by the wing nut 58. It will be noted that the device may be set up as shown in Fig. 1 so that the person can sit on seat 12 and use the table top 11. The person sitting on the seat may also rest his feet on the footrest 46.

It will be noted that the device may be collapsed in substantially flat shape bringing the table top 11 and seat 12 into the same plane. In Fig. 4 the device is shown in partially collapsed position, and in Fig. 5 in fully collapsed condition. After the device is collapsed the leg 13 may be slidably moved within the tube 41 to bring the table top 11 closer to the seat 12. Due to the fact that the leg 13 and tube 42 are square, the leg cannot turn in the tube.

If desired, the tube 42 may be omitted as shown in Fig. 7 in which case rod 21 and link 35 are hinged directly to spaced portions of the leg 13. As shown in Fig. 5 brackets 78 may be fixed to the leg 13 and provided with pivots 71 for the rod 21 and link 35.

It will be noted that link 32 is offset to one side of rod 21 so that it can lie alongside rod 21 and directly beneath the seat when the device is collapsed. Link 27a is in a plane parallel to and alongside the plane of link 32, when the device is collapsed. Link 35 is in a plane offset from the plane of link 27a so that it likewise can lie beneath the seat 12. It will be noted that the offset wall 55 on leg 13 permits the leg to lie below rod 21 and parallel thereto when the device is collapsed.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A device of the character described comprising a seat, a rear leg member pivoted to the seat and having means to engage a support for said device at more than one point, a rod fixed to the seat and extending forwardly therefrom, a link pivoted at one end to the leg member, a second link pivoted at one end to the seat, and also pivoted to an intermediate portion of the first link, a third link pivoted at one end to the opposite end of the first link, a sleeve pivoted at spaced points to the rod and third link, a front leg slidably in said sleeve, and a table top mounted at the upper end of the front leg.

2. A device of the character described comprising a seat, a rear leg member pivoted to the seat and having means to engage a support for said device at more than one point, a rod fixed to the seat and extending forwardly therefrom, a link pivoted at one end to the leg member, a second link pivoted at one end to the seat, and also pivoted to an intermediate portion of the first link, a third link pivoted at one end to the opposite end of the first link, a sleeve pivoted

5 at spaced points to the rod and third link, a front leg slidably in said sleeve, a table top mounted at the upper end of the front leg, and means to fix the table top to the upper end of the front leg in various angular positions.

3. A device of the character described comprising a seat, a rear leg member pivoted to the underside of the seat at a point adjacent the rear end of the seat and having a plurality of leg portions, a rod fixed to the underside of the seat and extending forwardly therefrom, a link pivoted at one end to said rear leg member, a second link pivotally connected to the underside of the seat and having a pivot connected with an intermediate portion of the first link, a third link pivoted at one end of the opposite end of said first link, a front leg member having a pivotal connection with said rod and third link, and a table top at the upper end of said front leg member.

4. A device of the character described comprising a seat, a pair of bearings at the underside of the seat, and adjacent the rear edge thereof, a rear leg member having a horizontal portion journalled in said bearings, and a pair of parallel downwardly extending legs, a sleeve fixed to the underside of the seat and disposed at right angles to said bearings, a rod passing through the sleeve and having a bearing at its rear end rotatably receiving the horizontal portion of said rear leg member, a brace interconnecting the legs of said rear leg member, a link pivoted at one end to said brace, a second link pivoted at one end to the underside of said seat, said second link being pivoted to an intermediate portion of the first link, a third link pivoted at one end to the opposite end of the first link, a front leg member extending above the seat, means to connect the front leg member to the forward ends 20 of the rod and third link for pivotal movement relative thereto, a table top, a bracket fixed to the underside of the table top and formed with a longitudinal slot, a bolt at the upper end of said front leg, and passing through the slot, and means to tighten the bolt for fixing the bracket to the upper end of the front leg in various longitudinal and angular positions.

5. A device of the character described comprising a seat, a pair of bearings at the underside of the seat, and adjacent the rear edge thereof, a rear leg member having a horizontal portion journalled in said bearings, and a pair of parallel downwardly extending legs, a sleeve fixed to the underside of the seat and disposed at right angles to said bearings, a rod passing through the sleeve and having a bearing at its rear end rotatably receiving the horizontal portion of said rear leg member, a brace interconnecting the legs of said rear leg member, a link pivoted at one end to said brace, a second link pivoted at one end to the underside of said seat, said second link being pivoted to an intermediate portion of the first link, a third link pivoted at one end to the opposite end of the first link, a front leg member 30 extending above the seat, means to connect the front leg member to the forward ends of the rod and third link for pivotal movement relative thereto, a table top, a bracket fixed to the underside of the table top and formed with longitudinal slot, a bolt at the upper end of said front leg, and passing through the slot, means to tighten the bolt for fixing the bracket to the upper end of the front leg in various longitudinal and angular positions, and means to prevent side 35 shifting of the rear leg member.

6. A device of the character described comprising a seat, a rear leg member pivoted to the seat and having spaced ground engaging means, a rod fixed to the seat and extending forwardly therefrom, a link pivoted at one end to the leg member, a second link pivoted at one end to the seat, and also pivoted to an intermediate portion of the first link, a third link pivoted at one end to the opposite end of the first link, a sleeve of non-circular cross-section pivoted at spaced points to the rod and third link, a front leg 10 slidably in said sleeve, and a table top mounted at the upper end of the front leg, said front leg being slidably mounted in said sleeve and of corresponding cross-section thereby preventing relative rotation between the sleeve and leg.

7. In combination, a seat, a rear leg member pivoted to the seat and having spaced ground engaging means, a link pivoted to said rear leg member, a second link pivoted to said seat and first link, a third link pivoted to the first link, a front leg member, means fixed to the seat and having a pivotal connection with said front leg member, said third link having a pivotal connection with said front leg member, and a table 20 top on said front leg member.

8. In combination, a seat, a rear leg member pivoted to the underside of the seat adjacent the rear edge of the seat and having spaced ground engaging means, a link pivoted at one end to said 30

rear leg member, a second link pivoted to the seat and having a pivotal connection with the first link, a third link pivoted to the first link, a rod fixed to the underside of the seat and extending forwardly therefrom, a sleeve of non-circular cross-section, the front end of the rod being pivoted to the upper end of the sleeve, the front end of the third link being pivoted to the lower end of the sleeve, a front leg member 15 slidably mounted in said sleeve and being of corresponding cross-section to prevent relative rotation, and extending up above the seat, said front leg member having an offset at its upper end, and a table top having a sliding pivotal connection to said offset.
